UNITED STATES PATENT OFFICE.

JOSEPH R. PALMENBERG, OF NEW YORK, N. Y.

DESIGN FOR A HAT-RACK.

SPECIFICATION forming part of Design No. 17,098, dated February 8, 1887.

Application filed January 3, 1887. Serial No. 223,337. Term of patent 14 years.

To all whom it may concern:

Be it known that I, JOSEPH R. PALMENBERG, a citizen of the United States, residing at New York, in the county and State of New York, have invented a new and original Design for Hat-Racks, of which the following is a specification.

The drawing represents a perspective view of my newly-designed hat rack.

This invention relates to a novel design for a hat-rack; and its leading feature consists of a standard projecting upwardly from a foot and provided with laterally-projecting arms that carry U-shaped supports, having a short front arm and a longer rear arm and provided with head-pieces.

In the drawing, *a* represents a standard pro-

jecting upward from a circular foot, *b*, and provided with laterally-projecting arms *c*. Each arm *c* carries U-shaped supports *d*, having a short front arm, *e*, and a longer rear arm, *f*. Each of the arms *c* is provided with a head, *g*. *h* are rods joining every pair of long arms *f*.

What I claim is—

The design for a hat-rack, consisting of standard *a*, foot *b*, arms *c*, and of the U-shaped supports *d*, having a short front arm, *e*, and a longer rear arm, *f*, the arms *c*, *f* carrying heads *g*, substantially as herein shown and described. 25 30

J. R. PALMENBERG.
